CORE WINDING MACHINE AND METHOD
Horace Clifford Westcott, Lemont, and Richard M. Ryde,
Oak Park, Ill., assignors to Hubbard and Company,
Chicago, Ill., a corporation of Pennsylvania
Filed Jan. 25, 1961, Ser. No. 84,805
6 Claims. (Cl. 242—56.2)

This invention relates in general to a magnetic core circuit for a transformer or the like and in particular to a machine for automatically forming the magnetic core circuit.

In the co-pending application entitled Transformer Core Construction, filed on March 13, 1961, bearing the Serial No. 95,056 and assigned to the same assignee as the present invention, there has been taught how to provide a new and improved magnetic core circuit and said application should be consulted for the details of the disclosure. Inasmuch as core circuits of the type disclosed in the aforementioned co-pending application will find a great demand in the transformer field, it is very important that the cost of producing such magnetic core circuits be kept to a minimum and such is the object of this invention.

Briefly, in the invention a magnetic core circuit of a predetermined configuration is assembled by the machine from a continuous insulated strip of magnetic core material. The continuous strip of magnetic core material is evenly guided through the machine and while moving is cut in a predetermined manner and wound tightly on a provided core form.

More specifically, in the illustrated embodiment of the invention, means are provided in the machine: to position a reel of magnetic core material; to automatically unwind the reel of magnetic core material and pass it through the machine; to guide the magnetic core material as it passes through the machine; to cut the magnetic core material as it passes through the machine in accordance with a predetermined program designed to enable a predetermined magnetic core circuit configuration to be wound on a magnetic core form; to further guide and center the cut core material as it continues through the machine; to wind the cut magnetic core material on a core form; and to insure that the cut magnetic core material is wound tightly on the core form.

The teachings of the invention will be more fully understood if the following is viewed in light of the drawings of which:

FIG. 1 is a plan view of a magnetic core winding machine embodying the features of the invention.

FIG. 2 is a side elevational view of the embodiment of the invention illustrated in FIG. 1.

FIG. 3 is an elevational view taken along the line 3—3 in FIG. 1.

FIG. 4 is a perspective view illustrating that portion of the machine illustrated in FIG. 1 at which the magnetic core circuit is wound on a magnetic core form.

FIG. 5 is a perspective view similar to that of FIG. 4 with the exception that the core form is rotated.

FIG. 6 is a perspective view illustrating the portion of the machine illustrated in FIG. 1 at which the magnetic core circuit is wound on a magnetic core form and more specifically illustrating the drive means through which the magnetic core circuit is tightly wound on the provided magnetic core.

FIG. 7 is a partly cut-away plan view illustrating the guide mechanism embodying the features of the invention that insures that a properly orientated magnetic core circuit is wound upon the provided magnetic core form.

FIG. 8 is an elevational view taken along the line 8—8 in FIG. 7.

2

FIG. 9 is an elevational view taken along the line 9—9 in FIG. 7.

FIG. 10 is a fragmentary elevational view taken along the line 10—10 in FIG. 8.

5 FIG. 11 is a fragmentary elevational view of the embodiment of the invention illustrated in FIG. 7.

FIG. 12 is an elevational view taken along the line 12—12 in FIG. 1.

10 FIG. 13 is an enlarged and cross-sectional fragmentary view of a portion of the machine illustrated in FIG. 12.

FIG. 14 is a plan view taken along the line 14—14 in FIG. 12.

15 FIG. 15 is a plan view of a particular magnetic core configuration which may be wound by the core winding machine illustrated in the drawings and embodying the features of the invention.

FIG. 16 is a cross-sectional view taken through the core illustrated in FIG. 15.

Referring now to the drawings and particularly to

20 FIGS. 1 and 2, there is illustrated a machine embodying the features of the invention. Moving from right to left, as seen in FIGS. 1 and 2, there is illustrated the reel assembly 20, the edge guide assembly 30, the reel unwind mechanism and magnetic core strip ma-

25 terial cutting assembly 40, the cut magnetic core guide assembly 50 and the winder assembly 60. The component parts in the machine are all mounted on a frame 70 comprised of appropriately welded or otherwise se-

25 cured channel members. Drive means (not shown) are provided for all the appropriate component parts of the

30 machine and the prime mover of the drive means is preferably an electric motor (not shown). The details of the drive means are not illustrated in the drawings inasmuch as the particular means utilized (but not

35 shown) to provide the necessary drive means is not considered a part of the invention and can be supplied by anyone skilled in the art. Several air operated cylinders are utilized in the embodiment of the invention illustrated in the drawings as will be seen and these air

40 operated cylinders may be purchased on the open market and the details do not involve any of the inventive concepts of this invention. Further control valves for these cylinders are also not shown, but here again these valves can be purchased on the open market and no inventive

45 skill is required to properly position and connect these valves and such is left to the ordinary skilled mechanic.

A reel of core material 22 comprised of a continuous strip of insulated magnetic core material is mounted on the reel assembly 20 and the leading edge of the

50 magnetic core material is threaded through the initial edge guide assembly 30. A trough 32 is provided in the edge guide assembly 30 and the trough 32 has dimensions slightly exceeding the normal width dimen-

55 sions of the continuous strip of insulated magnetic core material and thus acts to guide the continuous strip of magnetic core material into the reel unwind mechanism and magnetic core strip material cutting assembly 40.

The reel unwind mechanism comprises a pair of pinch drive rollers 42. The plurality of pinch drive rollers

60 42 engage the continuous strip of magnetic material and unwind the continuous strip of magnetic material from the reel 22 and pull the strip of magnetic core material through the trough 32 in the edge guide assembly 30 and into the reel unwind mechanism and magnetic

65 core strip material cutting assembly 40 through the input guide rollers 43. After the machine is set up and as

70 will be seen, input guide rollers 43 do not actively unwind the reel 22 of magnetic core material, but act generally as guide rollers. The lower pinch drive roller 42, as viewed in FIGURE 2, is pivoted and moved into a cooperating relationship with the upper pinch roller

42, as viewed in FIGURE 2, by means of the air cylinders 44.

The continuous strip of magnetic core material is pulled through the reel unwind mechanism and magnetic core strip material cutting assembly 40 and two pairs of cooperating rotary cutters 415, 416 and 417, 418 are positioned on opposite sides of the strip of magnetic core material. The cooperating pairs of rotary cutters 415, 416 and 417, 418 positioned on opposite sides of the strip of magnetic core material are cammed so as to follow a predetermined pattern and can move towards one another or away from one another, respectively, in accordance with a predetermined pattern as will be more fully seen hereinafter.

The continuous strip of magnetic core material moves from the reel 22 through the edge guide assembly 30 and through the reel unwind mechanism and magnetic core strip material cutting assembly 40 at a regular constant speed and as determined by the speed of rotation of the pinch drive rollers 42. Therefore, the strip of magnetic core material moves and is pushed out of the assembly 40 at a constant speed. However, the particular core wound in the illustrated embodiment of the invention is substantially rectangular in plan and it is easily understood that the winding of a strip of material on a rectangular form will not provide a regular constant speed to the peripheral movement of the strip of material.

If, for example, the winder assembly 60 were pulling the strip of magnetic core material through the entire machine, then the strip of magnetic core material would move through the machine in a staccato-type fashion and this would result in backlash, improper shearing, and the like. The pinch drive rollers 42 pull the strip of core material from the reel 22 through the edge guide assembly 30 and the reel unwind mechanism and magnetic core strip material cutting assembly 40 and pushes the strip of core material out the other side as illustrated in FIG. 2 and a sufficient quantity of magnetic core material is allowed to accumulate in a loop 51 so as to adjust for the winding of the magnetic core material on the core form 61 in the winder assembly 60. The magnetic core material in the illustrated embodiment of the invention is cut on both edges in a predetermined manner, and therefore in order to insure that the magnetic core circuit will be properly wound on the core form 61 in the winder assembly 60, a cut magnetic core guide assembly 50 is provided.

The cut magnetic core guide assembly 50 centers the strip of magnetic core material before the magnetic core material is wound on the core form 61 positioned in the winder assembly 60. The leading edge of the strip of magnetic core material is secured to the core form 61 in any convenient manner and the drive means of the core forming machine is then energized. In response to the energization of the drive means (not shown) the core form 61 rotates and begins to wind a magnetic core circuit upon itself. The winder assembly 60 is also provided with an air actuated magnetic core wrap assembly 650. The magnetic core wrap assembly 650 exerts a constant pressure on the outer layer of the magnetic core circuit being wound on the core form 61 and is particularly adapted to also tightly wind the magnetic core material around the substantially square corners of the core form 61.

The machine can be better understood if some detail is given to the various assemblies comprising the machine.

Winder Mechanism 60

The function of the winder mechanism 60 is to readily position a provided core form around which a magnetic core circuit is wound; to tightly wind the continuous strip of core material around the provided core form and to enable the finished magnetic core circuit to be readily removed from the winder mechanism 60.

Referring now in detail to FIGS. 3 through 6, it can

be seen that the winder mechanism 60 is mounted on the frame 70 and the winder mechanism 60 comprises a pair of rotatable and laterally shiftable core positioning shafts 601 and 602, respectively. The core form positioning shafts 601 and 602 extend through the fixed housings 603 and 604 respectively, into the driven rotatable bearing housings 605 and 606 respectively. The bearing housings 605 and 606 are keyed to the core form positioning shafts 601 and 602 so as to be rotatable in unison with the core form positioning shafts 601 and 602 and the bearing housings 605 and 606 are driven by a sprocket and chain arrangement (the details of which are not fully shown). The bearing housing 605 is driven by the sprocket, chain arrangement 607 and 608 and the bearing housing 606 is driven by the sprocket, chain arrangement 609 and 610, respectively. The bearing housings 605 and 606 are so connected to the core form positioning shafts 601 and 602 that the bearing housings 605 and 606 rotate in unison with the positioning shafts 601 and 602 respectively. However, the core form positioning shafts 601 and 602 may move inwardly and outwardly relative to the bearing housings 605 and 606 respectively. The above may be readily accomplished by providing a longitudinal slot in the positioning shafts 601 and 602 and by positioning a key element in the bearing housings 605 and 606, thereby allowing the positioning shafts 601 and 602 to move inwardly and outwardly with respect to the bearing housings 605 and 606 and to rotate in unison with respect to the bearing housings 605 and 606.

The core form positioning shafts 602 and 602 may move in or out—that is, towards one another or away from one another, in response to the movement of the pressure-actuated arms 611 and 612, respectively. The pressure-actuated arms 611 and 612 may be formed integrally on the core positioning shafts 601 and 602. The inward or outward movement of the pressure-actuated arms 611 and 612 causes the inward or outward movement of the core form positioning arms 601 and 602 respectively. The pressure-actuated arm 611 is moved inwardly and outwardly in response to the positioning of the actuating arm 613. The actuating arm 613 is pivoted at 614 on the pivot arm 615. The pivot arm 615 is pivoted on the frame structure 70 about the pin 616 so as to permit the pressure-actuated arm 611 to move inwardly and outwardly within the bearing housing 605. The actuating arm 613 is moved responsive to the position of the pressure cylinder arm 619 of the pressure-actuated cylinder 618. The pressure cylinder arm 619 is secured to the activating arm 613 at the pin 620. Movement of the pressure cylinder arm 619 inwardly or outwardly will cause a resultant movement of the pressure-actuated arm 611 and consequently the core positioning shaft 601 inwardly or outwardly within the bearing housing 605.

Similarly, the pressure-actuated arm 612 is moved inwardly and outwardly in response to the movement of the actuating arm 621. The actuating arm 621 is pivoted at 622 on the pivot arm 623. The pivot arm 623 is pivoted on the frame structure 70 about the pin 624 so as to permit the pressure-actuated arm 612 to move inwardly and outwardly within the bearing housing 606. The actuating arm 621 is moved responsive to the activation of the pressure cylinder 625. The pressure cylinder 625 is suitably affixed to the frame 70 and is provided with a pressure cylinder arm 626. The pressure cylinder arm 626 is pivotably attached to the activating arm 621 about pin 627. The movement of the pressure cylinder arm 626 causes the inward or outward movement of the pressure-actuated arm 612 thereby determining the position of the core form positioning shaft 602.

Initially the core form positioning shafts 601 and 602 are in an open position as illustrated in FIGURE 3. A core form is selected and the core form positioning shafts 601 and 602 are moved inwardly or towards one another by actuating the air pressure cylinder 618 and 625, respectively. A stop ring (not shown) is mounted within the

bearing housing 606 and the stop ring (not shown) serves to limit the inward movement of the core positioning shaft 602 to thereby aid in the centering of the core form 61. The activating mechanism associated with the air pressure cylinder 625 is so designed to exert a force on the core positioning shaft 602 which exceeds the force exerted on the core positioning shaft 601 by the activating mechanism associated with the air pressure cylinder 618, thereby insuring the centering of the core form 61 by the stop ring (not shown) mounted within the bearing housing 606. In the illustrated embodiment of the invention, the core positioning shaft 601 is provided with a substantially rectangular end piece 630 adapted to fit flush against the core form 61. The core positioning shaft 602 is provided with a somewhat I-shaped end 631, adapted to fit in and to secure the core form 61 tightly in place as is clearly evident in the drawings and especially FIGURES 4 and 5.

The core form 61 illustrated in the drawings is rectangular in configuration and, therefore, it can be appreciated that ordinarily it would be very difficult to tightly wind a continuous strip of magnetic core material on the core form 61 because of the non-regular motion of the rectangular core form 61 as it rotates and also because of the presence of corners on the core form 61.

In order to tightly wrap the magnetic core circuit on the core form 61, the magnetic core wrap assembly 650 is provided. The magnetic core wrap assembly 650 is pivotally attached to the frame 70 at 651, and the magnetic core wrap assembly 650 comprises a pair of longitudinal frame elements 652 and 653 interconnected by a pair of cross beams 654 and 655. The longitudinal frame elements are pivotably attached to the frame 70 at 651 and in any convenient manner. The upper end of the magnetic core wrap assembly 650 as viewed in the drawings has pivotably attached thereto a pair of substantially U-shaped secondary wrapping brackets 656. Positioned at the outer ends of the substantially U-shaped secondary wrapping bracket 656 are a pair of substantially U-shaped primary wrapping brackets 657 and a pair of substantially U-shaped primary wrapping brackets 658. Pivotably attached to each leg of each pair of substantially U-shaped primary wrapping brackets 657 and 658 are a pair of wrapping rollers bearing the designations 659, 660, 661 and 662, respectively. The magnetic core wrap assembly 650 is pivoted about the frame 70 at 651 by an air pressure cylinder 665 having extended therefrom a piston arm 666. The piston arm 666 is pivotably attached to the cross beam 654 as clearly indicated in FIGURE 6. The air pressure cylinder 665 is in turn mounted to the frame 70 in any convenient manner. The air pressure cylinder is so designed (the design not being a part of the invention) that a predetermined force is exerted on the cross beam 654 by the piston arm 666 of the air cylinder 665. This force exerted by the piston arm 666 tends to pivot the magnetic core wrap assembly 650 in a counter-clockwise direction as viewed in FIGS. 4 and 5.

The force exerted on the core wrap assembly 60 rotates the wrapping rollers 659, 660, 661 and 662 respectively as far in a counter-clockwise direction, as viewed in FIGS. 4 and 5, as possible. After the core form 61 has been positioned by the core positioning shafts 601 and 602 and air pressure cylinder 665 energized, the wrapping rollers 659, 660, 661 and 662 respectively, will press against the core form 61 and in such a way that each wrapping roller will tend to move counter-clockwise as far as possible and will thus exert a pressure on the core form 661 over a substantial area of the core form 61. The wrapping rollers 659, 660, 661 and 662 will therefore follow the surface of the core form 61 and due to the pressure exerted by the air pressure cylinder 665, will tightly adhere to the surface of the core form 61. The wrapping rollers will follow the contour of the core form 61 even around the edges of the core form 61 as

can be clearly seen in FIG. 5. When the magnetic core circuit is being wrapped on core form 61, it can be seen that the wrapping rollers 659, 660, 661 and 662 respectively will exert a force over a substantial surface of the magnetic circuit and will insure that the magnetic core circuit being wrapped on the core form 61 will tightly adhere to the core form 61 and subsequent wrappings will tightly adhere to one another even in those areas wherein the magnetic circuit turns a corner.

10 *Reel Unwind Mechanism and Magnetic Core Strip Material Cutting Assembly 40*

The general functions of the reel unwind mechanism and magnetic core strip material cutting assembly 40 are to unwind the reel 22 and to continuously cut the strip of magnetic core material passing therethrough in accordance with a predetermined pattern. In the illustrated embodiment of the invention the magnetic core material passing through the reel unwind mechanism and magnetic core strip material cutting assembly 40 is cut in a manner so as to produce a magnetic core circuit of a substantially semi-circular configuration. FIGURE 15 schematically illustrates a plan view of one type of magnetic core circuit which may be wound by use of the machine embodying the features of the invention. FIG. 16 illustrates the cross section of the type of magnetic core circuit illustrated in FIG. 15. It can be seen that the cross section is not entirely semi-circular inasmuch as there is a flattened inner end.

15 It should be realized at this time that the invention is not limited to the forming of magnetic circuits of the type illustrated in FIGS. 15 and 16 and that any reasonable pattern may be cut in the reel unwind mechanism and magnetic core strip material cutting assembly 40 although my aforementioned co-pending application has taught that the magnetic core circuit illustrated in FIGS. 15 and 16 has significant merit.

20 Referring to FIGS. 1 and 2, the reel unwind mechanism comprises a pair of pinch rollers 42 one of which is rigidly attached to a frame element 421 of the frame assembly 70. The other pinch roller 42 is pivotably attached to the frame assembly 70 and is pivotable into and out of operating position under the control of the pair of air pressure cylinders 44. The pair of pinch rollers 42 are driven by driving means (not shown) and merely serve the function of pulling the continuous strip of magnetic core material through the reel unwind mechanism and magnetic core strip material cutting assembly 40 at a constant and predetermined rate. It is believed that the ultimate details of the reel unwind mechanism may be supplied by any one skilled in the art and the mere statement of function would be sufficient to enable one skilled in the art to provide an operative reel unwind mechanism suitable for operation in the machine embodying the features of the invention.

25 The pinch rollers 43 illustrated in the drawings may perform the same function as the pinch rollers 42, however, in the disclosed embodiment of the invention it was found that the pinch rollers 43 need not be driving elements and they merely serve as guide rollers except when the continuous strip of magnetic core material is initially forced through the magnetic core strip material cutting assembly as will be more apparent later.

30 The magnetic core strip material cutting assembly is illustrated in FIGS. 1, 2, 12, 13 and 14 and the general function thereof is to cut a continuous strip of magnetic core circuit material in a predetermined pattern.

35 In the embodiment of the invention illustrated in the drawings, a pair of cooperating cutting edges are positioned on each side of the continuous strip of magnetic circuit core material and the continuous strip of magnetic circuit core material is pulled through the cooperating cutting edges. Further, the pair of cooperating cutting edges positioned on each side of the continuous strip of magnetic circuit core material are adapted to move inwardly and outwardly, that is, towards one another or

away from one another and therefore must be properly programmed to provide the desired over-all configuration for the finished magnetic core circuit.

The magnetic core strip material cutting assembly comprises a pair of frustum-shaped supporting brackets 401 and 402 secured to the frame 70 by any convenient means such as the mounting brackets 403, 404, 405 and 406 and a plurality of machine bolts 407. A pair of slideable frame members 408 and 409 are slidably mounted on a pair of parallel spaced shafts 410 and 411. The shafts 410 and 411 are rigidly fixed to the supporting brackets 401 and 402 by a plurality of machine bolts 413. Rigidly and removably affixed to each of the slideable frame members 408 and 409 are two pairs of cooperating cutters 415, 416 and 417, 418, respectively. The cutters 415, 416, 417 and 418 are removably secured to the slideable frame members 408 and 409 by a plurality of machine nuts 429. Each machine nut 429 is affixed to a threaded portion provided on the main shaft of each of the cutters 415, 416, 417 and 418, respectively.

The slideably mounted frame members 408 and 409, carrying the cooperating cutters 415, 416 and 417, 418, respectively, are each secured to the slotted drive block members 430 and 431 respectively. The slotted drive block members 430 and 431 are secured to the slideable frame members 408 and 409 by a pair of machine bolts 432 and 433, respectively. The slotted drive block members 430 and 431 are formed of two split halves each secured to the other by a pair of machine bolts 435 and 436 respectively thereby forming the two drive slots 437 and 438.

Positioned immediately below the slotted drive blocks 430 and 431 as viewed in the drawings is the program drive plate 440. The program drive plate 440 is somewhat wing shaped and is provided with a pair of drive slots 451 and 451' and a pair of internally threaded attachments 441 and 442. The program drive plate 440 is mounted on a threaded drive screw 443 and is moved back and forth on the threaded drive screw 443 when the threaded drive screw 443 is rotated. A pair of bearing housings 445 and 446 are secured to the frame structure 70 by a plurality of machine bolts and the threaded drive screw 443 is arranged so as to be freely rotatable within the bearing housing 445 and 446. Attached to one end of the threaded drive screw 443 is the rotatable drive sprocket 447 which is in turn driven by the central or main drive means (not shown) of the machine.

The drive sprocket 447 is coupled to the drive means (not shown) rotating the core positioning shafts 601 and 602 and the rotation of the drive sprocket 447 bears a direct relationship to the rotation of the core form 61. The pitch of the threaded drive screw 443 and the threaded portions 441 and 442 of the program drive plate 440 and the rotational speed of the drive means 447 are so arranged that the program drive plate 440 moves a distance equal to the thickness of the strip of magnetic core material for each revolution of the core form 61.

Positioned immediately below the program drive plate 440 as shown in the drawings, are a pair of pivotable cutter drive arms 449 and 450 mounted to shafts 449a and 450a, respectively. The shafts 449a and 450a are mounted to the frame structure 70 through the bearing brackets 452 and 453, respectively, best illustrated in FIG. 12 of the drawings.

Rigidly attached to the pivotable drive arms 449 and 450 at the upper end thereof as viewed in the drawings are the program drive pins 455 and 456, respectively. The program drive pins 455 and 456 extend up through the drive slots 451 and 451' positioned in the program drive plate 440 and through the slots 437 and 438 positioned within the slotted drive blocks 430 and 431, respectively, as can be best seen in FIGS. 12 and 14.

An air cylinder (not shown) is coupled through levers and arms (not shown) to the bottom, as viewed in the drawings, of the pivotable drive arms 449 and 450 and

applies a positive biasing force to the pivotable drive arms 449 and 450 to help overcome the initial or starting friction encountered by the pivotable drive arms 449 and 450. This force is adjusted such that initial movement of the pivotable drive arms 449 and 450 does not occur due to this force and only aids in and does not cause the initial movement of the pivotable drive arms 449 and 450. Thereafter the air cylinder (not shown) aids in but does not control the movement of the pivotable drive arms 449 and 450 and the movement of the pivotable drive arms 449 and 450 is controlled by the movement of the program drive plate 440.

The magnetic core strip material cutting assembly is programmed in the illustrated embodiment of the invention to cut the strip of magnetic core material passing therethrough such that a magnetic core circuit will be wound on the core form 61 of a substantially semi-circular cross section. This is accomplished by coupling the drive gear 447 of the magnetic core strip material cutting assembly to the drive means of the core winder (not shown) such that the drive gear 447 causes the program drive plate 440 to move a distance equal to the thickness of the magnetic circuit core material for each complete revolution of the core form 61. Assume that the program drive plate 440 is driven in a downward direction as viewed in FIG. 14 or into the paper as viewed in FIG. 12 as the core form 61 rotates in the machine. The movement of the program drive plate 440 causes the program drive pins 455 and 456 attached to the pivotable cutter drive arms 449 and 450 respectively to move in the slots 451 and 451' of the program drive plate 440 and the slots 437 and 438 of the drive blocks 430 and 431, respectively, to thereby cause the slideable frames 408 and 409 to move away from one another. The distance that the slideable frames 408 and 409 move away from each other is determined by the movement of the program drive plate 440 and the length of the pivotable cutter drive arms 449 and 450. Therefore, inasmuch as the distance that the program drive plate 440 moves in one revolution of the core form 61 is known (equal to the thickness of the magnetic core material) in the embodiment of the invention illustrated in the drawings, it is relatively simple to determine the desirable length of the pivotable cutter drive arms 449 and 450 and this length should be equal to the desired radius of the magnetic core circuit to be formed by the machine. Therefore, the width of the leading edge of the continuous strip of magnetic core material can be easily compensated for by the proper initial angular setting of the pivotable cutter drive arms 449 and 450. It should be understood that various rotary cutter programming can be adapted for the machine without departing from the inventive scope of the invention. What has been shown is the rotary cutter programming designed to provide a wound magnetic core circuit of a substantially semi-circular cross-section.

FIGURE 13 is a more detailed view of the slideable frame 408 and its associated pair of cooperating cutters 415 and 416. An integrally formed sleeve member 461 is securely attached to the slideable frame 408 and an integrally formed sleeve member 462 is secured to the slideable frame member 409. The rotary cutters 415, 416, 417 and 418 are mounted eccentric to their main shafts 463, 464, 465 and 466 respectively so that the rotary cutters can be readily resharpened and then the clearance re-established inasmuch as the diameters of the knife blades such as knife blade 474 of the rotary cutter 416 is decreased by sharpening.

The rotary cutter 416, for example, comprises a partially threaded main shaft 464 rigidly mounted to the slideable frame 408 by a machine bolt 429, an inner blade housing 468 rigidly attached to the main shaft 464 and thereby also secured from relative movement with respect to the slideable frame 408 by the machine bolt 429, and an outer blade housing 469 adapted to revolve around the inner housing 468. The inner blade housing 468 is pro-

vided with a plurality of oil retaining ridges 470. The outer blade housing 469 rotates about the inner blade housing 468 on a plurality of pressed-in roller bearings 471. The inner blade housing 468 is secured in a rotatable position with respect to the outer blade housing 469 by means of the inner blade housing end plate 472. The inner blade housing end plate 472 is secured to the inner blade housing 468 by a plurality of machine screws 473. The outer blade housing 469 includes the rotary knife 474 and the rotary knife stripper 475. The rotary cutter 418 is a twin of the rotary cutter 416 and the rotary cutters 415 and 417 are similar to the rotary cutter 416 with the exceptions that the rotary knives of the rotary cutters 415 and 417 are positioned on the inside, that is, closer to the slideable frames 408 and 409 than are the rotary cutters 416 and 418 and also the inner blade housings of the rotary cutters 415 and 417 are shorter than those of the rotary cutters 416 and 418 in order to properly position the cooperating rotary blades of the cooperating rotary cutters 415, 416 and 417, 418.

The Cut Magnetic Core Guide Assembly 50

FIGURE 1, 2 and 7 through 11 illustrate the cut magnetic core guide assembly 50. After the continuous strip of core material is cut in and pushed out of the reel unwind mechanism and magnetic core strip material cutting assembly 40, the cut strip of magnetic core material is wound on the core form 61 in a manner as previously described. The scrap from the continuous strip of magnetic core material is then fed to a scrap chopper (not shown) or otherwise disposed. It is apparent that if a magnetic core circuit is to be wound into any predetermined configuration, that the orientation of the core material as it is wound on the core form 61 is very important. In other words, the strip of magnetic core material is not allowed to wander and this is essential when a magnetic core circuit of a substantially semi-circular configuration is desired to be wound on the core form 61. Any meandering or wandering of the strip of magnetic core material between the reel unwind mechanism and magnetic core strip material cutting assembly 40 and the winder assembly 60 will result in a distortion of the cross-section of the finished magnetic core circuit.

Inasmuch as the cutting of the continuous strip of magnetic core material occurs on both edges of the magnetic core material, difficulty is found in properly aligning the cut magnetic core material. Therefore, there has been provided a cut magnetic core guide assembly 50 which insures the proper alignment and centering of the strip of cut magnetic core material.

First, however, it should be pointed out that the machine is in no way limited to the provision of magnetic core circuit which is wound from a cut continuous core of magnetic material wherein the cutting of the continuous core of magnetic material occurs along both edges of the magnetic core material.

More specifically, the cut magnetic core guide assembly 50 is attached to the frame structure 70 by a pair of substantially L-shaped brackets 501 and 502, as best seen in FIGS. 1 and 2. The continuous strip of magnetic core material is passed through the guide assembly 50 and the guide assembly 50 maintains the cut magnetic core material centered about a predetermined adjustable center line within the cut magnetic core guide assembly 50 itself.

The cut magnetic core guide assembly 50 comprises a guide assembly frame 505 comprising side plates 506 and 507. Fastened to the side plates 506 and 507 are a pair of mounting plates 508 and 509, each secured at one end of the side plates 506 and 507 by a plurality of machine screws. Mounted on the guide assembly frame 505 are a pair of magnetic core strip material restriction plates 510 and 511. The restriction plates 510 and 511 are mounted on the guide assembly frame 505 by a plurality of machine bolts 512. The plurality of ma-

chine bolts 512 are secured to a plurality of restriction plate mounting brackets 513 which are in turn secured to the guide assembly frame 505 by a plurality of machine bolts. The magnetic core strip material restriction plates 510 and 511 are spaced from one another approximately the distance equal to the thickness of the magnetic core strip material.

Affixed to the guide assembly frame 505 are two pair of cooperating ratcheted strip guide arm 503 and 504, respectively, best illustrated in FIG. 7. The pair of cooperating ratcheted strip guide arms 503 are pivotably secured to an adjustable guide arm shaft 514 at the pivot points 515 and 516 respectively. Each of the pair of cooperating ratcheted strip guide arm 504 are pivotably affixed to a adjustable guide arm shaft 517 at the pivot points 518 and 519, respectively. The adjustable guide arm shafts 514 and 517 are positioned below the restriction plates 510 and 511 as can be clearly seen in the drawings and particularly FIGS. 7 through 11. The adjustable guide arm shafts 514 and 517 are mounted to the guide assembly frame 505 in any convenient manner and the adjustable guide arm shafts 514 and 517 are threaded through their length and threaded apertures are provided in the side plates 506 and 507 in order that the adjustable guide shafts 514 and 517 may be moved back and forth across the width or narrower portion of the cut magnetic core guide assembly 50. A pair of adjustment wheels 520 and 521 are provided for the adjustable guide arm shafts 514 and 517 to manually adjust the position of the adjustable guide arm shafts 514 and 517. Each of the ratcheted strip guide arms 503 and 504 are provided with a strip guide roller 522 positioned at the ends of the ratcheted strip guide arms 503 and 504. The strip guide rollers 522 are pivotably secured to the guide arms 503 and 504 by a plurality of fixed rivet pins 523. As can be seen the ratcheted strip guide arms 503 and 504 extend past the front end 524 and rear end 525 of the magnetic core strip material restriction plates 510 and 511 and this is best illustrated in FIGS. 7 and 8. The pair of cooperating ratcheted strip guide arms 503 and 504 are so arranged as to be movable towards one another or away from one another so as to center the continuous strip of magnetic core material being transmitted through the cut magnetic core guide assembly 50. The cooperating ratcheted strip guide arm 503 and 504 are connected to an air cylinder 530. The pair of ratcheted strip guide arms 503 are pivotably attached to the air cylinder 530 at the pivot point 531. The pair of ratcheted strip guide arms 504 are pivotably attached to the air cylinder 530 at the pivot point 532. The air cylinder 530 is connected to a source of air pressure (not shown) and the piston arm 533 of the air cylinder 530 exerts a predetermined pressure or force on the pair of guide arms 503 through the pivot point 531 and inasmuch as the air cylinder 530 is free to move a force or reaction force is exerted on the pair of guide arm 504 through the pivot points 532. The action of the air cylinder 530 pushes the pair of guide arms 503 toward one another and the pair of guide arms 504 toward one another and this motion continues until a resistive force equal to the force exerted by the air cylinder 530 is encountered and this force will be the resistive force of the edges of the cut strip of magnetic core material being transmitted through the cut magnetic core guide assembly 50.

Also mounted on the guide assembly frame 505 are two pairs of air actuated tension rollers 535, 536 and 537, 538, respectively. The tension rollers 535, 536, 537 and 538 are operable into an open position and a closed position, and when in the closed position serve to help keep the continuous strip of magnetic core material taut as the continuous strip of cut magnetic core material is pulled through the cut magnetic core guide assembly 50 by the winder assembly 60. The tension rollers 535 and 537 are rigidly fixed to the guide assembly frame 505 and are positioned in a pair of bearing housings 540 and 541,

respectively. The tension rollers 536 and 538 are operable from an open position as shown in FIG. 8 to a closed position as shown in FIGS. 10 and 11, and the tension rollers 536 and 538 are moved from the open position to the closed position by a pair of air cylinders 542 and 543, respectively. The air cylinders 542 and 543 are supplied from a source of air pressure (not shown) and may be manually controlled by any suitable control mechanism (not shown).

Positioned on the magnetic core strip material restriction plate 510 is an anti-backlash block assembly comprising the substantially cylindrical anti-backlash air cylinder 550. The anti-backlash air cylinder 550 is rigidly secured to the restriction plate 510 by the machine screws 551. Positioned within the anti-backlash air cylinder 550 is the anti-backlash hard wooden block piston 553. The anti-backlash hard wooden block piston 553 can be adjustably moved downwardly by adjusting the air pressure in contact with the top of the anti-backlash hard wooden block piston 553 by adjusting means (not shown). The anti-backlash wooden block piston 553 is preferably composed of a hard wood, although other materials which would not scratch the insulation off the continuous strip of magnetic core material passing through the restriction plates 510 and 511 can be used.

The purpose of providing the anti-backlash assembly is to apply a drag to the continuous strip of magnetic core material to keep the continuous strip of magnetic core material taut as it passes through the cut magnetic core guide assembly 50 thereby aiding in the tight wrapping of the continuous strip of magnetic material on the core form 61.

Reel Assembly 20 and Edge Guide Assembly 30

The reel assembly 20 and the edge guide assembly 30 are comparatively simple in construction. The edge guide assembly 30 consists of a trestle-like structure supported at one end on the frame structure 70 and on the other end by a pair of supporting legs 31. A pair of longitudinally extending angle members 33 are positioned on the edge guide assembly 30 to form a trough 32 through which the continuous strip of magnetic core material is guided. The width dimensions of the trough 32 slightly exceed the width dimension of the continuous strip of magnetic core material and therefore the edges of the continuous strip of magnetic core material are oriented by the channel members 33 forming the trough 32.

The reel assembly 20 comprises a supporting base 21 secured to the main frame structure 70 in any convenient manner. Positioned on the main support 21 is the pair of upright supporting beams 23. The reel 22 of magnetic core material is positioned in provided slots in the pair of upright supporting beams 23 such that the reel 22 of magnetic core material can freely rotate in the supporting beams 23.

Operation

Initially, a continuous reel of magnetic core material is mounted in place in the reel assembly 20. The particular configuration and arrangement of the reel assembly 20 is not essential to the practice of the invention, the only requirement being that a continuous strip of magnetic core material be capable of being delivered from the reel assembly 20. The leading edge of the continuous strip of magnetic core material is then delivered to the edge guide assembly 30 wherein it passes through and it is guided in the trough 32 of the edge guide assembly 30.

The leading edge of the continuous strip of magnetic core material is then delivered to the reel unwind mechanism and magnetic core strip material cutting assembly 40. The leading edge of the continuous strip of magnetic core material is then threaded between the guide rollers 43. The guide rollers 43 are at this part of the cycle of the machine and only this part of the cycle of the machine operated by the same drive means (not shown) that operate the pinch drive rollers 42 and the guide rollers

43 are here used to force the continuous strip of magnetic core material through the properly spaced rotary cutters 415, 416, 417 and 418 until the cut continuous strip of magnetic core material is gripped by the pinch drive rollers 42. Thereafter the guide rollers 43 are rendered inoperative by means not shown and act only as guide rollers thereafter.

The cutters 415, 416, 417 and 418 best seen in FIGS. 12 and 13 are eccentrically mounted on their respective main shafts 463, 464, 465 and 466 and therefore cooperating pairs of cutters 415, 416 and 417, 418 respectively can be moved away from one another or toward one another by rotating the main shafts 463, 464, 465 and 466 in their associated movable frames 408 and 409, respectively. Thus it becomes relatively simple to reposition the rotary cutters to a precise and predetermined spacing after the rotary cutters have been sharpened. The leading edge of the continuous strip of magnetic core material is driven between the cooperating cutters 415, 416, 417 and 418 respectively by the guide rollers 43 until the leading edge of the strip of magnetic core material is engaged by the pinch drive rollers 42 as previously explained.

The pinch drive rollers 42 have an operative and inoperative position as determined by the energization of the air cylinders 44 and the resultant pivoting of the lower arm adjusting levers illustrated in FIGS. 1 and 2. Therefore, as soon as the leading edge of the strip of magnetic core material is drawn up to the pinch drive rollers 42, the pinch drive rollers are then placed in an operative position by manipulating the air cylinders 44. The drive means (not shown) and which can be any conventional drive means, such as an electric motor prime mover and associated chains and sprockets, is then momentarily energized so that the leading portion of the continuous strip of magnetic core material is pulled through the edge guide assembly 30 and the reel unwind mechanism and magnetic core strip material cutting assembly 40 by the action of the pinch drive rollers 42. After a sufficiently long strip of magnetic core material has been pulled through the last mentioned mechanisms to form the loop 51 shown in FIG. 2, the cut continuous strip of magnetic core material is then threaded through the cut magnetic core guide assembly 50 and, finally, secured to the core form 61 in the winder assembly 60 by any convenient means, such as insulating tape or providing a slot therefor in the core form 61, or whatever means is most convenient.

Previous to the securing of the cut continuous strip of magnetic core material to the core form 61, the core form 61 itself is positioned in the winder assembly 60 by first actuating the air cylinders 618 and 625. The actuation of the air cylinders 618 and 625 will move the core positioning shafts 601 and 602 towards one another. The core 61 may be held in the center manually until the core positioning shafts 601 and 602 move to the center and align with one another to securely position the core form 61.

After the leading edge of the magnetic core material has been secured to the core form 61, the air cylinder 530 in the cut magnetic core guide assembly 50 is energized from a source of air pressure (not shown) to thereby move the pair of ratchet strip guide arms 503 towards one another until the strip guide rollers 522 engage the sides of the cut continuous magnetic core material. Movement of the two pairs of ratcheted strip guide arms 503 and 504 will continue until the cut continuous strip of magnetic core material is centered between the pairs of ratcheted strip guide arms 503 and 504, and if necessary one of the ratcheted strip guide arms 503 or 504 will push the edge of the cut continuous strip of magnetic core material over until the entire width of the cut continuous strip of magnetic core material is centered between the pairs of ratcheted strip guide arms 503 and 504.

The position of the pairs of ratcheted strip guide arms 503 and 504 can be adjusted by adjusting the adjustable guide arm shafts 514 and 517 by turning the adjustment

wheels 520 and 521, respectively. Therefore, shades of misalignment between the core form 61 and the cut continuous strip of magnetic core material can be compensated for by use of these adjustable guide arm shafts 514 and 517. After the cut continuous strip of magnetic core material has been properly aligned with the core form 61, the air pistons 542 and 543 operatively associated with the tension rollers 536 and 538 may be energized from the source of air pressure (not shown) and the tension rollers 536 and 538 will move from an open position as shown in FIG. 8 to a closed position as shown in FIGS. 10 and 11. Thereafter, the magnetic core wrap assembly 650 is positioned in an operative position by energizing the air cylinder 665. The air cylinder 665 is energized from a source not shown.

Before the drive means (not shown) of the core forming machine are actuated to automatically form a magnetic core circuit, calculations must be made to determine the programming of the rotary cutters 415, 416, 417 and 418, respectively. In the embodiment of the invention illustrated in the drawings it has been decided to form a magnetic core circuit with a substantially semi-circular cross-section. It can be noticed in FIG. 16 that the cross-section is not absolutely semi-circular, but is somewhat flattened at the inner end. This flattening is a practical compromise inasmuch as the apex of the semi-circle would have zero width and therefore would be impractical to form. Therefore, the inner end of the magnetic core circuit formed by the core forming machine is somewhat flattened. The drive mechanism (not shown) is then adjusted such that for every revolution of the core form 61, the program drive plate 440 will be moved a distance equal to the thickness of the continuous strip of magnetic core material. As was previously explained, the provision of the slots 451 and 451' and in the program drive plate 440 and the slots 438 and 437 in the drive blocks 431 and 430, respectively, enables the slideable frame supports 408 and 409 to move away from one another at such a rate that the end result or the configuration of the magnetic core circuit will be substantially semi-circular and will be of a configuration illustrated in FIGS. 15 and 16.

Means such as the length of core winding indicator 80 schematically illustrated in FIG. 2 may be provided in the machine to automatically stop the machine after a predetermined magnetic core circuit has been wound upon the core form 61 as will be explained later. The pinch drive rollers 42 are activated as previously described to draw the continuous strip of magnetic core material through the edge guide assembly 30, through the guide rollers 43, through the cooperating rotary cutters 415, 416 and 417, 418, respectively, and push the cut core material out of the reel unwind mechanism and magnetic core strip material cutting assembly 40 into the loop 51 as illustrated in FIG. 2. The core form 61 is rotated by the rotation of the core form positioning shafts 601 and 602 and the magnetic core wrap assembly 650 exerts a constant pressure on the continuous strip of magnetic core material as it is wound upon the core form 61. The magnetic core wrap assembly is constructed such that the continuous strip of magnetic core material is tightly pressed to the core form 61 and subsequent layers of the magnetic core material are tightly pressed to one another and the pivotability of the magnetic core wrap assembly rollers 659, 660, 661 and 662 enable the constant pressure to be applied to the continuous strip of magnetic core material being wrapped even when going around the corners of the core form 61, as is clearly illustrated in FIG. 5.

The motion of the cut continuous strip of magnetic core material after it emerges from the pinch rollers 42 is staccato-like in nature in that the peripheral speed of the continuous strip of magnetic core material changes depending upon the position of the core form 61 because the core form 61 is rectangular in configuration. Also,

the peripheral speed of the continuous strip of magnetic core material increases slowly because the periphery of the magnetic core circuit being formed is increasing and therefore the peripheral speed is increasing. The speed of the pinch drive rollers 42 is slowly increased by means (not shown) to maintain the size of loop 51 approximately the same at all times. Therefore, the build-up of the loop 51 adjacent the drive pinch rollers 42 enables the cutting of the continuous strip of magnetic core material to be smooth and even as it passes through the reel unwind mechanism and magnetic core strip cutting assembly 40 is constant. The staccato-type movement of the continuous strip of magnetic core material after it emerges from the driven pinch rollers 42 is adjusted for by enabling the loop 51 to be built up in the mechanism.

As the cut continuous strip of magnetic core material passes through the cut magnetic core guide assembly 50, the width of the continuous strip of magnetic core material increases. The pairs of ratcheted strip guide arms 503 and 504 move away from one another in response to the counter pressure exerted by the edges of the cut continuous strip of magnetic core material and must move in unison and therefore the cut strip of magnetic core material will be symmetrical about a chosen center line, and the center line is determined by the position of the adjustable guide arms shafts 514 and 517. Therefore, a symmetrical magnetic core circuit is provided.

The length of core winding indicator means 80 schematically illustrated in FIG. 2 can be adjusted to automatically stop the machine after a predetermined magnetic core circuit has been wound upon the core form 61 as for example by interrupting the energizing circuit of the prime mover (not shown) if, for example, the prime mover is an electric motor.

In a preferred embodiment of the invention a digital computer device which translates length or distance into a predetermined number of counts is utilized in the length of core winding indicator means 80. A transducer including the schematically illustrated roller 801 is located adjacent the tension roller 535 and rotates therewith. Means not shown, are provided in the digital computer device to reset the digital computer device to zero each time the core form 61 makes a full revolution. Initially a count corresponding to the desired perimeter of the last turn of the magnetic core circuit is manually set in the digital computer device. As the magnetic core circuit is being formed the length or perimeter of each winding on the magnetic core circuit is fed into the digital computer by means of the transducer (not shown) including the schematically illustrated roller 801. When the length of the winding being wound on the magnetic core circuit approaches the preset count, means (not shown) can be provided to slow down the drive means (not shown) if desired. Finally, the length or perimeter of the winding being wound or the magnetic core circuit exceeds the preset length and means (not shown) provided in the length of core winding indicator 80 are provided to stop the machine.

Specific details of the length of core winding indicator 80 are not provided inasmuch as equipment is presently on the market to accomplish the manipulations necessary and to give the output or machine stop signal required without inventive adaptation of the equipment.

What has been described is considered to be the preferred embodiment of the invention. However, alterations, modifications, substitutions and the like, may be made without departing from the scope of the invention. Therefore, it is the intention that the claims appended hereto cover the entire inventive scope disclosed in the foregoing.

What is claimed is:

1. A machine for winding a magnetic core circuit comprising, a reel mechanism for delivering a continuous strip of magnetic core material, a rotary cutter assembly for continuously cutting said continuous strip of magnetic

core material, said rotary cutter assembly comprised of at least two pair of rotary cutters spaced from one another and adapted to cut adjacent opposite edges of said continuous strip of magnetic core material, drive means for said continuous strip of magnetic core material to pull said continuous strip of magnetic core material from said reel mechanism and through said rotary cutter assembly at a constant speed, a winder assembly for tightly wrapping said cut continuous strip of magnetic core material on a provided core form, a guide mechanism for orientating said cut continuous strip of magnetic core material about a predetermined point before said cut continuous strip of magnetic core material is wound on said provided core form by said winder assembly, said pairs of rotary cutters in said rotary cutter assembly being movable relative to one another, means for programming the relative movement of said pairs of said rotary cutters in said rotary cutter assembly responsive to the winding of said continuous strip of magnetic core material on said provided core form, and magnetic core circuit length means for determining the length of the final wrapping of said magnetic core circuit for interrupting the wrapping of said continuous strip of magnetic core material on said provided core thereby enabling said continuous strip of magnetic core material to be so cut that a magnetic core circuit of a predetermined configuration is wound on said provided core form by said winder assembly.

2. A process for forming a magnetic core circuit of a predetermined configuration on a polygonal-shaped core form, comprising the steps of: providing a continuous strip of magnetic core material, delivering said continuous strip of magnetic core material to a continuous cutter assembly at a constant speed, continuously cutting said continuous strip of magnetic core material in said continuous cutter assembly, building up a loop of said continuous strip of magnetic core material after said continuous strip of magnetic core material is cut in said continuously cutting cutter assembly, delivering said continuous strip of magnetic core material from said loop to a winder assembly, winding said continuous strip of magnetic core material on said polygonal-shaped core form in said winder assembly, and programming the cutting of said continuous strip of magnetic core material in said continuous cutter assembly in accordance with the winding of said continuous strip of magnetic core material in said winder assembly.

3. A mechanism for continuously cutting a moving strip of material comprising a first movable rotary cutter frame having positioned thereon a first pair of cooperating rotary cutter blades, a second movable rotary cutter frame having positioned thereon a second pair of cooperating rotary cutter blades, said first movable rotary cutter frame and said second movable rotary cutter frame being movable toward one another and away from one another, and means for programming the movement of said first and said second movable rotary cutter frames whereby said moving strip of material can be cut by said first pair of cooperating rotary cutter blades and said second pair of cooperating rotary cutter blades such that a magnetic core configuration of predetermined cross-section can be assembled, and said first and second movable rotary cutter frames being slidably mounted upon a pair of parallel spaced shaft members, said first and second frames being secured to a first and second drive block member, respectively, said first and second drive block members each having a slot therein, said slot in said first and second drive block members being substantially parallel, said first and second frames being connected to a program drive plate having slots therein extending transversely of said slots in said first and second drive block members, said program drive plate being adapted to be moved in a direction substantially parallel to said slots in said first and second drive block members whereby said first and second frame members move toward or away from one another.

4. A machine for winding a magnetic core circuit com-

prising, a reel mechanism for delivering a continuous strip of magnetic core material, a rotary cutter assembly for continuously cutting said continuous strip of magnetic core material, said rotary cutter assembly comprised of at least two pair of rotary cutters spaced from one another and adapted to cut adjacent opposite edges of said continuous strip of magnetic core material, a first guide means for guiding said continuous strip of magnetic core material from said reel mechanism to said rotary cutter assembly comprising a fixed trough having width dimensions slightly exceeding the width dimensions of said continuous strip of magnetic core material, drive means for said continuous strip of magnetic core material operable to pull said continuous strip of magnetic core material from said reel mechanism and through said trough in said first guide means and through said rotary cutter assembly at a constant speed to thereby cause said continuous strip of magnetic core material to be cut in said rotary cutter assembly by said pairs of rotary cutters, a winder assembly including a pivotal pressure element having two spaced contact surfaces for engaging and for tightly wrapping the cut continuous strip of magnetic core material on a provided core form, a second guide mechanism for orientating said cut continuous strip of magnetic core material about a predetermined point before said cut continuous strip of magnetic core material is wound on said provided core form by said winder assembly, said pairs of rotary cutters of said rotary cutter assembly being movable relative to one another, and means for programming the relative movement of said pairs of said rotary cutters responsive to the winding of said cut continuous strip of magnetic core material in said winder assembly, one pair of rotary cutters being mounted upon a first cutter frame and the other pair of rotary cutters being mounted upon a second cutter frame, said first and second cutter frames being slidably mounted upon a pair of parallel spaced shaft members, said first and second cutter frames being secured to a first and second drive block member, respectively, said first and second drive block members each having a slot therein, said slots in said drive block members being substantially parallel, said first and second cutter frames being connected to a program drive plate having slots therein which extend transversely to said slots in said first and second drive block members, said program drive plate being adapted to be moved in a direction substantially parallel to said slots in said drive program members whereby said cutter frames are moved toward or away from one another.

5. A machine for winding a magnetic core circuit comprising, a reel mechanism for delivering a continuous strip of magnetic core material, a rotary cutter assembly for continuously cutting said continuous strip of magnetic core material, said rotary cutter assembly comprised of at least two pair of rotary cutters spaced from one another and adapted to cut adjacent opposite edges of said continuous strip of magnetic core material, a first guide means for guiding said continuous strip of magnetic core material from said reel mechanism to said rotary cutter assembly comprising a fixed trough having width dimensions slightly exceeding the width dimensions of said continuous strip of magnetic core material, drive means for said continuous strip of magnetic core material operable to pull said continuous strip of magnetic core material from said reel mechanism and through said trough in said first guide means and through said rotary cutter assembly at a constant speed to thereby cause said continuous strip of magnetic core material to be cut in said rotary cutter assembly by said pairs of rotary cutters, a winder assembly including a pivotal pressure element having two spaced contact surfaces for engaging and for tightly wrapping the cut continuous strip of magnetic core material on a provided core form, a second guide mechanism for orientating said cut continuous strip of magnetic core material about a pre-

terminated point before said cut continuous strip of magnetic core material is wound on said provided core form by said winder assembly, said pairs of rotary cutters of said rotary cutter assembly being movable relative to one another, and means for programming the relative movement of said pairs of said rotary cutters responsive to the winding of said cut continuous strip of magnetic core material in said winder assembly, one pair of rotary cutters being mounted upon a first cutter frame and the other pair of rotary cutters being mounted upon a second cutter frame, said first and second cutter frames being connected to a program drive plate whereby movement of said program drive plate moves said first and second cutter frames toward and away from one another, and means for driving said program drive plate, said means for driving said program drive plate also driving said winder assembly.

6. The machine of claim 4 wherein a second drive means is provided for the said winder assembly, said second drive means also driving said program drive plate. 20
